CLAIM

The ornamental design for a tumbler lid as shown and described.

DESCRIPTION

FIG. 1 is a front, right, and top perspective view of my new design for a tumbler lid shown in an assembled configuration;

FIG. 2 is an exploded front, right, and top perspective view thereof;

FIG. 3 is a front, right, and top perspective view of a first piece of a tumbler lid, shown separately for clarity of disclosure;

FIG. 4 is a rear, left and bottom perspective view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a top plan view thereof;

FIG. 10 is a bottom plan view thereof;

FIG. 11 is a rear, left, and top perspective view of a second piece of a tumbler lid, shown separately for clarity of disclosure;

FIG. 12 is a front, right and bottom perspective view thereof;

FIG. 13 is a front elevation view thereof;

FIG. 14 is a rear elevation view thereof;

FIG. 15 is a right side elevation view thereof;

FIG. 16 is a left side elevation view thereof;

FIG. 17 is a top plan view thereof; and,

FIG. 18 is a bottom plan view thereof.

The broken lines are included for the purposes of illustrating portions of the tumbler lid that form no part of the claimed design.

1 Claim, 18 Drawing Sheets
